US00D765690S

(12) United States Design Patent (10) Patent No.: US D765,690 S
Lee et al. (45) Date of Patent: * Sep. 6, 2016

(54) DISPLAY SCREEN OR PORTION THEREOF WITH GRAPHICAL USER INTERFACE

(71) Applicant: Samsung Electronics Co., Ltd., Suwon-Si, Gyeonggi-Do (KR)

(72) Inventors: Min Sun Lee, Seoul (KR); Olivia Lee, Seoul (KR); Han Chul Jung, Seongnam-si (KR)

(73) Assignee: Samsung Electronics Co., Ltd., Gyeonggi-do (KR)

() Term: 14 Years

(21) Appl. No.: 29/498,905

(22) Filed: Aug. 8, 2014

(30) Foreign Application Priority Data

Feb. 11, 2014 (KR) 30-2014-0006880

(57) CLAIM

The ornamental design for a display screen or portion thereof with graphical user interface, as shown and described.

DESCRIPTION

FIG. 1 is the front view for a display screen or portion thereof with graphical user interface showing our new design; and,

FIG. 2 is the enlarged front view of the graphical user interface of FIG. 1 for clarity of disclosure.

The dot-dash line showing of a display screen or portion thereof forms no part of the claimed design. The remaining broken lines showing portions of the graphical user interface form no part of the claimed design.

1 Claim, 2 Drawing Sheets
